UNITED STATES PATENT OFFICE.

JOSÉ S. CAMACHO, OF HABANA, CUBA.

IMPROVEMENT IN RAILWAY CAR-TRUCKS.

Specification forming part of Letters Patent No. 128,533, dated July 2, 1872.

Specification describing a new and Improved Truck for Railroad Cars, invented by José S. CAMACHO, of Habana, in the Island of Cuba.

Figure 1 represents a sectional side view of my invention. Fig. 2 is a bottom view of the same. Figs. 3 and 4 are vertical transverse sections of the same taken on the planes of lines *c c* and *k k*, Fig. 1, respectively.

Similar letters of reference indicate corresponding parts.

This invention has for its object to insure the proper position of wheels of railroad cars while running on curves; and the invention consists in the arrangement of a swivel-frame holding two pairs of wheels, so that each wheel can turn independent of the others, as hereinafter more fully described.

A in the drawing represents part of the body of a railroad car or engine. *B* is a metal frame, carrying the axles *a a* of two wheels, *C C*, said axles being in line with but disconnected from each other. The pivot *b*, by which the frame *B* is connected to the car, is, as near as possible, in line with the axis of the wheels *C C*,

thereby making it so much easier for the wheels to swing in position to fit a curve than when the pivot is further away from the axle. The axles *a a* will, moreover, be nearly or entirely parallel with the radius of the curve on which the wheels *C* run. In arms *d d*, projecting forward from the frame *B*, are the bearings of two disconnected axles, *e e*, upon which smaller wheels *D D* are mounted. These latter have the sole object of keeping the wheels *C* opposite each other on the curve, preventing them from twisting and binding on the rails.

Having thus described my invention, I claim as new and desire to secure by Letters Patent—

The swivel-frame *B*, provided with the arms *d d*, and furnishing bearings for the axles *a a* and *e e* of the wheels *C C* and *D D*, substantially as and for the purpose herein shown and described.

JOSÉ S. CAMACHO.
